UNITED STATES PATENT OFFICE

WILLIAM A. NORRIS, OF ALHAMBRA, CALIFORNIA

CIGARETTE

Application filed October 31, 1932. Serial No. 640,381.

This invention relates to improvements in cigarettes and in their method of manufacture.

The general object of this invention is to provide a cigarette including means to direct the smoke thereof through the cigarette in a spiral course.

Another object of the invention is to provide a cigarette made with tobacco wherein the tobacco strands are twisted or in spiral formation.

Other objects and the advantages of this invention will be apparent from the following description taken in connection with the accompanying drawing wherein:

Fig. 1 is a perspective view of my improved cigarette showing a portion of the wrapping removed.

Fig. 2 is a diagrammatic view showing an apparatus for making my improved cigarette.

Fig. 3 is an enlarged fragmentary section taken on line 3—3 of Fig. 2.

Fig. 4 is an enlarged section taken on line 4—4 of Fig. 2.

Fig. 5 is an enlarged section taken on line 5—5 of Fig. 2.

Fig. 6 is an enlarged section taken on line 6—6 of Fig. 2.

Fig. 7 is an enlarged section taken on line 7—7 of Fig. 2 and

Fig. 8 is an enlarged section taken on line 8—8 of Fig. 2.

Referring to the drawing by reference characters, I have indicated my improved cigarette generally at 10. As shown the cigarette 10 is similar in general appearance to the standard type cigarette and includes a tubular casing 12 having a filler 13 therein. The casing 12 may be made of any type of paper commonly used for cigarette wrapping.

The filler 14 is made of tobacco with the strands twisted in spiral formation as indicated by the strand shown in a heavy line at 14 in Fig. 1. By making the filler 13 in spiral formation as shown the sum of the lengths of the strands of tobacco is greater than if the filler was formed of straight laid strands while the number of strands is less.

When the cigarette 10 is lighted the ends of the tobacco strands burn with a rotary di-

rection as the burning front recedes and when the smoke therefrom is drawn through the cigarette from the lighted end to the mouth the tobacco strands direct the smoke in a spiral course. This causes the smoke to travel a greater distance than if it merely passed through the cigarette in a straight line and thus the smoke has a greater length of time to cool off between the lighted end and the unlighted end.

In Figs. 2 to 8 inclusive, I have shown diagrammatically a machine of novel construction which produces my cigarette by a novel method. As shown tobacco 15 is fed into a tray 16 from a hopper 17. The tray 16 is inclined downwardly towards a vertical funnel member 18 and is resiliently supported as indicated at 19. The tray 16 is adapted to be vibrated by a plurality of cam members 21 to cause the fibres of the tobacco to lie longitudinally in the tray and feed into the funnel member 18 in longitudinal alignment. From the funnel member 18 the tobacco passes into a twisting tube 22 which may be rotated by a worm gear 23 from a worm pinion 24. Adjacent the lower end thereof the funnel member 18 includes a plurality of inwardly directed prongs 25 and the twisting tube 22 includes similar prongs 26. The prongs 25 in the funnel member 18 restrict rotation and aligns the tobacco as it passes downwardly therein while the prongs 26 in the twisting tube 22 engage the strands of tobacco and twist them about the axes of the tube thereby forming the tobacco into a spirally formed column 27 which emerges from the tubes 22 into a U-shaped channel of paper 28 (see Fig. 8).

The paper 28 is shown as fed from a roll 29 onto a continuously moving belt 30 which conveys the paper through a forming machine 31 wherein it is gradually shaped from a flat strip as shown in Fig. 8. After the paper emerges from the forming machine 31 the twisted tobacco member 27 is laid in the paper trough and the belt 30 carries the paper 28 and the tobacco rope 27 through a closing and seaming device 32 which may be of any desired construction wherein the paper is closed around the twisted tobacco column and

sealed. The tobacco emerges from the closing and sealing device 32 completely encased in a paper tube as indicated at 33. The belt 30 then conveys the member 33 through a cutting device 34 which may be of any desired construction and wherein the member 33 is cut into cigarette lengths. The belt 30 then expels the finished cigarettes into a chute 35.

The tobacco being laid in twists causes the 10 burning particles to advance in a circular course. This causes the aromas of the various blends of tobacco to become better mixed thus resulting in a better flavored smoke. The smoke in my cigarette travels a circular 15 course, it has a longer distance to go and thus has more time to cool off. Also, as the burning moves longitudinally and circumferentially there is a longer interval of burning and consequently each cigarette lasts longer 20 than the ordinary cigarette but at the same time no more tobacco is employed in making the cigarette. Furthermore, since the tobacco is laid in twists it makes a stronger and more rigid cigarette because the twist causes 25 the strands of tobacco to contact one another and thus increases the strength and also causes a more even burning.

With the tobacco laid in a twist the very 30 fine particles which break off from the strands are held by the twist and are not drawn into the mouth. With my cigarette, 35 due to the strength given the cigarette by twisting, a lighter weight cigarette paper may be used which is advantageous because it 40 requires that less paper be burned.

From the foregoing description it will be apparent that I have provided a novel method and apparatus for making a novel cigarette.

Having thus described my invention, I 45 claim:

1. A cigarette comprising a wrapper and a filler, said filler consisting solely of tobacco particles including strings or threads, the individual strings or threads extending spirally of the length of the filler.

2. A cigarette including a wrapper and a filler, said filler consisting solely of tobacco particles, certain of said particles being elongated and of a length shorter than the length 55 of the filler and lying in spirals extending generally in the direction of the longitudinal axis of the filler.

3. The method of forming a cigarette comprising the step of arranging tobacco particles to form a filler with the longitudinal axes of individual particles extending in parallel lines, and then twisting the filler spirally upon its longitudinal axis.

4. The method of forming a cigarette comprising the step of arranging tobacco particles including strings or threads to form a filler, with the longitudinal axis of individual strings or threads extending generally in the direction of the length of the filler, twisting the filler upon its longitudinal axis so that

the strings or threads extend in a spiral, and enclosing the filler in a wrapper.

In testimony whereof, I hereunto affix my signature.

WILLIAM A. NORRIS.
